UNITED STATES PATENT OFFICE.

JOSEPH LA FOLLETTE, OF PORTLAND, OREGON.

COMBINATION BEVEL-PROTRACTOR.

1,028,742.

Specification of Letters Patent. Patented June 4, 1912.

Application filed July 28, 1911. Serial No. 641,154.

To all whom it may concern:

Be it known that I, JOSEPH LA FOLLETTE, a citizen of the United States, residing at Portland, in the county of Multnomah and 5 State of Oregon, have invented certain new and useful Improvements in Combination Bevel-Protractors, of which the following is a specification.

My invention relates to means for laying 10 out angles and computing lengths of material in building construction work, and is an improvement on an instrument of this character, for which Letters Patent of the United States were granted to me June 27th, 1911, 15 No. 996,591.

The object of my invention is to provide an instrument of this character, which can be used to advantage both by the mechanic erecting a building and the draftsman executing its design of construction.

To this end my device comprises a protractor plate and a set of independent attachments, the latter so constructed that any one of them best adapted to perform a certain function can be readily attached to the protractor plate. In this manner I provide an instrument of wide range of adaptability.

The construction and operation of my device will be readily understood by anyone 30 versed in the art by referring to the following description and the appended drawing, in which,

Figure 1 shows a protractor embodying my invention and provided with a straight-edge attachment, Fig. 2 is a front elevation of said straight-edge attachment, Fig. 3 illustrates my device fitted with a protractor stock, parts of said stock removed in order to clearly show its construction, and Fig. 40 is a perspective elevation of the protractor stock shown in Fig. 3.

Referring in the first instance to Fig. 1 plate or quadrant *a* is provided with a series of scales *c*, *d*, *e*, giving the angles of 45 side-cuts for roof-hips and valleys, and a protractor scale *b*, whereas the opposite face of the quadrant, as illustrated in Fig. 3, is made with a series of scales *f*, *g*, *h*, giving lengths of rafters and angles of their top and bottom cuts. This arrangement of 50 scales I have found most convenient in practice, but I wish it understood that I may substitute any other combination or arrangement of scales. Said scales are all 55 concentric, and plate *a* is at scale center *i*

made with a notch *j* adapted to receive pivot *k* of protractor stock *l*. The latter comprises two parts *m*, *m'*, identical in form and held together in their proper relation by studs *k* and *n*. On stud *n*, between parts *m*, *m'*, is rotatably hung an eccentric cam *o* provided with a fingerpiece *p*, and in close proximity to said cam is mounted a shoe *q*, held in place by one or more studs *r*. Perforations *s* of said shoe are elongated to 60 permit said shoe to move longitudinally in stock *l*. When desired to mount stock *l* on plate *a*, pivot *k* is first caused to enter notch *j*, whereupon the stock is rotated on said pivot, until shoe *q* engages and rides on 65 the peripheral surface *t* of the plate, as shown in Fig. 3, and it is readily seen that the stock, as long as the shoe is in engagement with edge *t*, is securely hung on the plate. The stock is set by turning it until 70 its reading edge *u* coincides with the desired reading on one of the scales, whereupon it is locked against peripheral displacement on the plate by rotating eccentric cam *o*, which in its turn clamps shoe *q* 75 against surface *t*.

Stock *l* is preferably made of thick material, so as to insure a good surface contact between said stock and the edge of the timber to be marked for cutting, but in order to provide a more convenient instrument for draftsmen's use, I substitute the combination shown in Fig. 1, in which a stock *v* is mounted on blade *a*. The construction of this stock, so far as the attaching and locking arrangements are concerned, is identical with the construction of stock *l*, but it differs from the latter in other respects. It is made in two parts *w*, *w'*, one of which, as *w'*, extends beyond pivot *y* 95 and forms a blade or straight-edge *x*.

Stock *v* is made of very thin metal, in order to be conveniently used on paper drawings, where my device may be used in connection with a T-square by bringing 100 either edge *z*, *z'* of the stock in contact with the edge of the T-square, or it may be used independently on oblique lines by alining an edge *z*, *z'* with said oblique line. Finally my device itself may be used as a T-square by placing edge 2 or 3 of plate *a* against the edge of the drawing board. In cases where fine protractor measurements are required, I may add a vernier scale as indicated by reference number 4 in Fig. 1. 110

Having thus described my invention, I claim:

1. In a device of the character described in combination with a quadrantal scale bearing plate provided at the apex with a notch the bottom of which coincides with the scale center, a pair of interchangeable stocks each adapted to fulcrum in the notch of said plate, and means for clamping the stocks on the plate, all as and for the purpose set forth.

2. In a device of the character described in combination with a quadrantal scale bearing plate provided at the apex with a notch the bottom of which coincides with

the scale center, a pair of interchangeable stocks, each stock comprising two members and provided with means for clamping the two members together, said means comprising two studs one at each end of the stock, 20 the inner stud adapted to fulcrum in said notch, and means for clamping the stock on the plate, said means coöperating with the outer stud, all for the purpose set forth.

In testimony whereof I affix my signature in presence of two witnesses.

JOSEPH LA FOLLETTE.

Witnesses:

C. C. ABBOTT,
K. F. DOUGHTY.
